DIAMOND BIT

Frank E. Koebel, Glen Ridge, and John H. Metz,
Verona, N. J., assignors to J. K. Smit & Sons,
Inc., New York, N. Y., a corporation of New
York

Application April 6, 1940, Serial No. 328,258

2 Claims. (Cl. 255—61)

This invention relates to the diamond bit industry and is particularly directed to blast hole drilling.

The development of diamond drilling as a means of replacing the percussion drill for blast hole work has created problems with respect to diamond bit design which have heretofore not been satisfactorily solved, and for the further economic and practical advancement of the art of diamond blast hole drilling, a diamond bit of much improved design is essential.

Various types of bits are being used for this work but in general they are designed to drill solid holes necessitating imposing tremendous pressures over the entire bit area with consequent excessive wear and high costs. As a consequence resort has been had to the thin wall coring type of bit which removes less rock and hence requires less pressure. However, such bits have inherent disadvantages in that the drill rods must be lifted to remove the core which is obtained with this type of bit. This of course increases labor costs appreciably.

One of the objects of this invention is the provision of a bit having the advantages of the thin wall coring bit so far as reduction in pressure is concerned, but with additional advantages in that we incorporate a core reducer and core breaker or crusher. It will be appreciated by those skilled in this art that such a tool will permit higher rotating speeds to be used and solid holes to be drilled at low pressure with a minimum consumption of power. It will be apparent also that drilling will be continuous inasmuch as the necessity of stopping at intervals for the removal of cores is eliminated.

In the accompanying drawing wherein we have illustrated an embodiment of our invention:

Fig. 1 is a sectional elevational view of a bit embodying our invention;

Fig. 2 is a plan view of Fig. 1; and

Fig. 3 is an exploded view of the bit of Figs. 1 and 2.

Referring to the drawing in detail: 2 designates a metal shell constituting the nose or forward end of our improved tool. This member 2 is faced with attrition elements such as commercial diamonds 4 and is integral with or rigid with the shank 6 of the tool.

Within the shank 6 and extending into the shell 2 is a core reducer 8. This is a cylindrical member faced at its forward end with attrition elements such as commercial diamonds 10. Peripheral flanges 12 are provided at the base of this core reducer, the upper face of the flanges 55

abutting the base of the shank 6 when the parts are assembled, as illustrated in Fig. 1.

The action of this core reducer 8 is to reduce the size of the core produced by the outer shell 2 which, as will be understood, leads the core reducer in the drilling operation, the opening 12 in the core reducer being materially smaller than the bore of the shell 2.

The wall of the core reducer 8 is provided with one or more radially extending bores 14. We have elected to show two, but any number that may be desired or found practicable may be employed. These bores have been shown cylindrical, but this, too, is merely for purposes of illustration. 15 The bores have been shown offset with respect to each other with respect to the longitudinal axis of the reducer. Their positioning in this regard may be varied also, as will be appreciated.

The radial bores 14 are provided for the reception of core crushers 16 which extend thereinto and project therefrom into the longitudinal bore 12 of the core reducer. These crushers may be simply cylindrical metal pieces, freely slidable in the radial bores 14 and of such a length that they project approximately half way across the longitudinal bore 12. The inner end of each of the crushers 16 is bevelled as illustrated, the bevelled portion being faced with diamonds, as shown at 18, to present faces extending diagonally of the axial bore 12 of the reducer 8. Retraction of the core crushers is prevented by the walls of the shank 6 and the shell 2.

The reducer 8 is of reduced diameter throughout part of its length, as shown at 20, to provide for the passage of flushing water between the reducer and the shell 2, while the lower part of the reducer is provided with waterways 22 leading from the bottom of the reducer to this reduced portion.

40 It will be apparent from all of the foregoing that upon rotation of our improved tool the core formed by the shell 2 entering the rock is engaged, as formed, by the core reducer 8 which very materially reduces its diameter, and that the relatively small core which remains is engaged by the crushers 16 which gradually wear it away until it is completely destroyed. As a result of our construction it will be appreciated that holes can be drilled at low pressure with a minimum consumption of power. It will be evident also that higher rotating speeds can be employed than heretofore, and that continuous drilling is practicable owing to the elimination of the necessity of removing cores.

It is to be understood that changes may be

made in the details of construction and arrangement of parts herein illustrated and described within the purview of our invention.

What we claim is:

1. A bit comprising in combination, a core-producing shell, a tool shank carrying said shell, a hollow cylindrical core-reducer lying within said shell and shank and terminating short of the end of the shell, said shell, shank and core-reducer being constructed and arranged to provide for the passage of a flushing fluid between the core reducer and the shank and shell to the forward end of the bit, and a core crusher extending radially through the wall of said reducer approximately to the center thereof so as to engage and destroy by attrition the reduced core passing through the core-reducer.

2. A combined core reducer and core crusher

for insertion into the core producing shell of a diamond bit, and comprising in combination a cylindrical member having a longitudinal bore, and reduced in diameter throughout part of its length, diamonds set into the forward or working end of said cylindrical member, grooves or waterways in the periphery of the cylindrical member extending lengthwise thereof, said grooves extending from the large end to the reduced portion of the cylindrical member, a core crusher extending through the reduced portion of the cylindrical member radially toward the axis of the said cylindrical member, the inner end of the crusher sloping toward the axis of the cylindrical member, and attrition elements set into this sloping end of the crusher.
